UNITED STATES PATENT OFFICE

2,402,408

SUSPENSION BRIDGE SADDLE

Sterling Johnston, Bethlehem, Pa., assignor to Bethlehem Steel Company, a corporation of Pennsylvania

Application October 22, 1943, Serial No. 507,242

6 Claims. (Cl. 14—22)

1

This invention relates to improvements in saddles for suspension bridge cables of the "open" type construction.

This type of cable, which may be well adapted for suspension bridges of comparatively short spans, comprises a plurality of spaced strands or ropes which are placed far enough apart to allow for inspection and painting. To effectively support the cable it is preferable to provide a saddle with definitely spaced grooves therein for each individual strand. Where the cable is made of a considerable number of strands it is customary to provide a saddle with grooves which are arranged to support a plurality of the strands in tiers. Heretofore the radii for all of the tiers of strands usually originated from a common center. This arrangement necessitated a different structure for each tier.

The present invention provides a saddle made up of a plurality of substantially identical members which are preferably made as finished castings requiring no expensive machining. These members can be constructed so that when angularly assembled as a saddle the radius of the ropes supported thereon in each tier is substantially the same.

In the accompanying drawings—

Figure 1 is a side view of the structure showing the saddle members supporting three vertical tiers of strands with a part of the outer web plate broken away.

Figure 2 is a cross sectional view on line 2—2 of Figure 1.

Figure 3 shows one of the individual strand supporting castings on a somewhat larger scale.

Figure 4 is a cross sectional view on line 4—4 of Figure 3.

Figure 5 is a view similar to Figure 4 but of a modified form of strand support using a "twin" type casting.

Figure 6 is a diagrammatic view of the saddle members indicating their relative locations in the structure.

Referring to the drawings more in detail, 10 designates a tower, having a cap plate 11 supported on the top thereof, to which spaced web plates 12 and 13 are attached by welding or other means. Mounted intermediate the web plates 12 and 13 are the saddle members 14 which are preferably provided with arcuate seats 15 to support the cable strands (or ropes) 16. Bolts 17 are provided to secure the saddle members 14 in their assembled relation with the web plates 12 and 13. Each of the bolts 17 extends through all of the web plates 12 and 13 through a plurality of

2

the members 14 and provides support for these members 14 as well as furnishing means for the transfer of the load from the saddle members to the web plates. The bolts 17 also serve as tension members for clamping the entire assembly compactly together. Stiffener plates 18 which are attached to web plates 12 and cap plate 11 give additional lateral support to the saddle structure. A cover plate 19 is fastened by bolts 20 to angles 21 and 22 which are welded to the web plates 12 providing means for protecting the assembly from the elements.

A clearance space 23 is provided between the adjacent ends of the saddle members 14, and the seats 15 for the strands 16 terminate a substantial distance from the ends of the members 14. By terminating the seats 15 short of the ends of the members 14 a more uniform structure is provided for the strands 16 as these strands will 20 frictionally engage the entire surface of the seats 15. The groove 24 requires no machine-finishing, the natural surface of the casting being sufficiently smooth so that it will not cause injury to the strand. The bolt holes 25 are 25 spaced so that the saddle members are reversible end for end.

In Figure 5 a "twin" type saddle member 114 is shown. With this type of construction a plurality of strands, instead of a single strand, in each tier may be supported between two web plates 112 and 113, thus reducing the number of web plates required while providing adequate support when the strands are of relatively small size.

35 The arrangement of the bolt holes 25' in the web plates for the bolts 17 as specifically shown in Figure 6 is an essential feature of my invention. The arrangement permits a plurality of saddle members 14 to be supported by means of the bolts 17 in such a relative position that the seats 15 form a continuous arc. The bolt holes when thus located on the arc of circles with equal radii r_1 , r_2 and r_3 will so position the saddle members 14 when they are assembled with web plates 12 through the medium of the bolts 17 that the seats 15 of the saddle members 14 of each tier will lie in a continuous arc, as shown in Figure 1.

While I have shown my invention in but two forms, it will be obvious to those skilled in the art that it is not so limited, but is susceptible of various changes and modifications without departing from the spirit thereof and I desire, therefore, that only such limitations shall be placed thereupon as are imposed by the prior art or as 55 are specifically set forth in the appended claims.

Having thus described my invention, what I claim as new and desire to secure by Letters Patent is:

1. A saddle comprising a plurality of assemblies arranged in tiers for supporting individual strands of a bridge cable, each of the assemblies comprising identical units angularly disposed to each other to provide a support of substantially the same radius for the strand irrespective of its location in the saddle.

2. A cable support comprising vertical web plates and saddles, said saddles comprising a plurality of arcuate strand supporting assemblies disposed intermediate the vertical web plates, the units of said assemblies being angularly disposed to each other to provide supports with identical radii for the strands irrespective of the location of the strands in the structure and means for positioning each assembly.

3. A cable support comprising parallel vertical web plates and saddles, said saddles comprising a plurality of identical assemblies for supporting the individual strands of a bridge cable, each assembly consisting of castings disposed at an angle to each other and having arcuate surfaces for supporting at least one of said strands and means for attaching said castings to the parallel web plates so that each assembly is supported in spaced relation to the adjacent assemblies.

4. A bridge cable support comprising a plurality of spaced vertical members and a plurality

of strand supporting units disposed intermediate said vertical members and substantially horizontally disposed fastening means extending through said vertical members and said supporting units to retain said members and units in their assembled condition, said fastening means positioning said strand supporting units in tiers intermediate the vertical members.

5. A bridge cable support comprising parallel vertical web plates and saddles disposed in tiers intermediate the vertical web plates, each of said saddles comprising a plurality of arcuate strand supporting units angularly disposed to each other to provide supports with identical radii for the strands irrespective of the location of the strand in the structure and means intermediate, and positioned by, the web plates for independently supporting each assembly.

6. A cable support comprising parallel vertical web plates and saddles, said saddles comprising a plurality of identical assemblies for supporting the individual strands of a bridge cable one above another, each assembly consisting of units disposed at an angle to each other and having arcuate surfaces for supporting at least one of said strands and means for attaching said units to the parallel web plates so that each unit is supported independently of any other unit lying at a different level in the structure.

STERLING JOHNSTON.
